R. J. Berry Attorney.

UNITED STATES PATENT OFFICE.

FRANK E. RANDALL, OF LOS ANGELES, CALIFORNIA, ASSIGNOR OF TWO-THIRDS TO
THEODORE HOLMES AND J. EDWARD GLENN, BOTH OF LOS ANGELES, CALIFORNIA.

ADJUSTABLE ERASER HOLDER.

Application filed February 16, 1926. Serial No. 88,539.

This invention relates to an eraser holder and particularly pertains to an eraser holding device of the magazine type.

The primary object of the invention is to provide a device adapted to contain an eraser and operable to feed the eraser from a magazine to present lengths of the eraser therefrom as occasion may require, whereby the protruding working end of the eraser may be advanced from time to time to compensate for wearing of the eraser under use.

Another object is to provide an eraser holder of the above character which is so constructed as to enable the ready removal and replacement of the eraser so as to facilitate renewal of the eraser when it becomes excessively worn.

Another object is to provide a magazine eraser holder which is adapted to be applied to a lead pencil, pen holder or the like.

A further object is to provide a magazine eraser holder which is simple in construction, easily operated, and which is durable and not liable to get out of order.

The invention resides generally in the provision of a tubular magazine open at least at one of its ends fitted with a slidable eraser carrier operable to be disposed in various positions longitudinally of the magazine whereby an eraser held in the carrier may be adjusted to vary the extent of its projection through the open end of the magazine.

The invention further resides in the parts and in the combination, construction and arrangement of parts hereinafter described and claimed and illustrated by way of example in the accompanying drawing, in which:—

Fig. 1 is a perspective view of the eraser holder;

Fig. 2 is a view in vertical section;

Fig. 3 is a detail in cross section as seen on the line 3—3 of Fig. 2;

Fig. 4 is a detail in cross section as seen on the line 4—4 of Fig. 2.

Referring to the drawings more specifically, 5 indicates a tubular magazine here shown as circular in cross section; being in the form of a cylinder open at its upper end. An elongated slot 6 extends longitudinally of the cylindrical magazine wall from a point adjacent the upper end thereof to a point any suitable distance therefrom and leading laterally from the slot 6 and communicating therewith is a series of transverse slots including end slots 7 and 8 and

a plurality of intermediate slots 9 suitably spaced apart and extending alternately from opposite sides of the longitudinal slots 6 between the end slots 7 and 8.

Arranged within the tubular magazine and slidable longitudinally thereof is an eraser carrier 10 on which is mounted an elongated cylindrical eraser 11. The carrier 10 is here shown as comprising an annulus, the outer periphery of which slidably conforms to the inner periphery of the tubular magazine and which annulus encircles the inner end of the eraser in frictional engagement therewith. The outer end portion of the eraser is formed of such diameter as to slidably conform to the inner periphery of the tubular magazine and its inner end portion is reduced in diameter so that it may be inserted within the annular carrier.

Detachably connected to the carrier 10 is a pin or stud 12 projecting through the slotted portion of the magazine, the outer end of which stud is formed with a head 13 and the inner end of which is formed with screw threads 14 engageable with a threaded opening 15 in the annular carrier. The inner end of the stud is extended through the walls of the carrier into engagement with the eraser thereby holding the latter against accidental disengagement from the carrier.

The magazine may be of any suitable length and may be formed with a tubular end extension as indicated at 16 adapted to receive the end portion of a pencil or pen holder 17 with which the magazine may be either fixedly or detachably connected.

In assembling the device, as in mounting the eraser within the magazine, the carrier 10 may be removed from the magazine on disengaging the stud 12 therefrom and after being engaged with the eraser replaced through the open outer end of the magazine; or the carrier may be disposed in its uppermost position in the magazine and the stud unscrewed to permit insertion of the inner end of the eraser within the carrier.

It will be apparent that by manipulating the stud the carrier may be turned circumferentially in relation to the magazine to dispose the stud in alignment with the longitudinal slot whereupon the carrier may be shifted longitudinally of the magazine by passing the stud along the slot 6 and may be disposed in various positions throughout the range of its length of move-

ment by switching the stud into engagement with any one of the transverse slots. The eraser is of such length in its normal state that its outer end will protrude a short distance from the end of the magazine when the carrier is in its innermost position as shown in Fig. 2.

In use, when the protruding end portion of the eraser wears away an additional length of the eraser may be projected from the magazine by shifting the carrier to a more advanced position by manipulating the stud as before described; the carrier being held against movement lengthwise of the magazine in any desired adjusted position in opposition to end thrusts imposed on the eraser by engaging the stud with one of the transverse slots. In this manner the eraser may be fed step by step as occasion may require by a new length of eraser in

the manner specified on removal of the worn eraser from the carrier.

I claim:—

An eraser holder comprising a tubiform body having a longitudinal slot, a ring-shaped eraser carrier fitted slidably within said tubiform body, a cylindrical eraser fitting slidably within said tubiform body, said eraser having a diametrically reduced inner end portion which fits within said ring-shaped carrier, said carrier being provided with a screw-threaded hole, and a stud slideable along the aforementioned slot, said stud being screwed into said hole in the eraser carrier and at its inner end projecting into said eraser to secure said eraser and carrier together.

In testimony whereof, I have affixed my signature.

FRANK E. RANDALL.
